KEY BLANK

Richard John Ohno, Branford, Conn., assignor to Sargent & Company, New Haven, Conn., a corporation of Connecticut

Filed Jan. 5, 1966, Ser. No. 476

Term of patent 14 years

(Cl. D50—4)

FIG. 1 is a plan view of a key blank embodying my design;

FIG. 2 is an edge view of the blank;

FIG. 3 is an end view of the key blank illustrating the tip end;

FIG. 4 is a sectional view taken along line 4—4 of FIG. 1;

FIG. 5 is a fragmentary, enlarged view similar to FIG. 1, illustrating the tip end of the key blank;

FIG. 6 is a view of the tip end of the blank taken at right angles to FIG. 5; and

FIG. 7 is a fragmentary view similar to FIG. 3 but on an enlarged scale.

The dominant features reside in the solid line showing.
I claim:

The ornamental design for a key blank, substantially as shown and described.
